PULSATATOR FOR MILKING APPARATUS

Robert W. Lemm, Grass Lake, Mich.

Application June 2, 1939, Serial No. 276,943

3 Claims. (Cl. 31—61)

My invention relates to pulsators for milking apparatus.

In a form of pulsator now quite generally used there are a rectangular metal block, or base, and two pairs of cylinder blocks secured to opposite sides of said metal block, with intervening gaskets, and passages passing longitudinally and transversely in three directions, into and through said metal block and communicating with the cylinders of said cylinder blocks through grooves formed in the side surfaces and covered with said gaskets, and passages in the cylinder blocks.

These passages open through the upper surface of said intermediate block and there are valves that are automatically actuated to slide transversely on the upper surface of said intermediate block and cooperate with the openings in said surface to put the vacuum, or atmospheric pressure, in communication with the usual rubber inflations of the teat-cups of the milking apparatus to secure the operation. This conventional construction involves long and intricate passages of small cross section, that are difficult and expensive to make, that are liable to clog up, and that are difficult to clean. Moreover, when such construction is taken apart for cleaning, it is often difficult for a mechanically unskilled person to get it together again in operative condition.

In the conventional construction, the length and intricacy of the passages causes dilatory action, and often a stoppage of the operation of the apparatus by reason of foreign matter entering the fine passages.

It is an object of my invention to eliminate all grooves from the side surfaces of the block and to make the passages short and straight so that the above noted objections to the conventional construction are obviated.

I secure this object by means of the construction shown in the accompanying drawing, in which:

Fig. 1 is a plan view, partly broken away, of a pulsator embodying my invention;

Fig. 2 is an end elevation, partly broken away, looking from the position indicated by the line 2—2;

Fig. 3 is a section on the broken section line 3—3, Fig. 1, the valve being shown in full section;

Fig. 4 is a section on the line 4—4, Fig. 1;

Fig. 5 is a front elevation of the apparatus shown in Fig. 1;

Fig. 6 is a view from below of the valve shown at the left of Fig. 1; and

Fig. 7 is a view from below of the valve shown at the right of Fig. 1.

Referring now to the drawing, I provide a rectangular base block 2 forming the base of the instrument and I provide cylinder blocks 3 and 4,

attaching them to opposite vertical sides of the block 2 by flanges *x* and screws *y*, as indicated in Figures 2, 3 and 5. Each cylinder block is provided with a pair of cylinders having their inner ends open and their outer ends closed, the cylinder block 3 having the cylinders 3a and 3b and the cylinder block 4 having the cylinders 4a and 4b.

In the cylinder block 3 I provide two straight passages 3c and 3d, the passage 3c opening to the outer end of the cylinder 3a and to the inner surface of the cylinder block 3 at the point 3e and the passage 3d opening to the outer end of the cylinder 3b and to the inner surface of the cylinder block 3 at the point 3f, said passages being preferably arranged in such a manner that their horizontal projections cross each other as indicated in Figure 1. The cylinder block 4 is provided with passages 4c and 4d entirely similar to the passages 3c and 3d, the passage 4c opening to the outer end of the cylinder 4a and to the inner surface of the cylinder block 4 at the point 4e and the passage 4d opening to the outer end of the cylinder 4b and to the inner surface of the cylinder block 4 at the point 4f.

From the center of the lower surface of the base 2, I bore a cavity 5. When the pulsator is in operative position the block 2 is placed on the cover 6 of the milk receptacle in such manner as to register with the suction opening thereof, not shown, which is usually provided in such covers so that suction in the cavity tends to cause a vacuum in the milk receptacle. In the base 2 there is also provided an axial bore 7 extending part way therethrough communicating with the cavity 5 and extending therebeyond for a purpose to be hereafter shown, and opening at one end of said base. A tube 8 is screw threaded or otherwise secured to the base 2 whereby to connect with the bore 7 and the cavity 5 so that a vacuum producing apparatus may be secured to the opposite end of the tube 8 to cause vacuum to be produced in the cavity 5 and in the bore 7.

In the base 2, I also provide two vertical passages 9 and 9a, each opening in the upper surface of the base and leading to the bore 7, said passages being at right angles to the said bore (Fig. 4). The said passages 9 and 9a are located in the longitudinal central line of the said surface and spaced a short distance apart in the right hand end of the base 2, as shown in Figure 1.

The base 2 has a diagonal passage 10 opening toward the upper surface thereof at a point located in the front of the passage 9a and extending in downward direction toward the end of the base opposite to the end to which the tube 8 is connected. The lower end of the passage 10 terminates in a screw thread opening 10b in said base and a metal tube 10c is screwed therewith. The tube 10c may be connected to any suitable

manifold, such as the manifold 11, which may be provided with any suitable tubes, such as metal tubes 11a, and they are adapted to communicate with the teat-cup inflations (not shown).

The base 2 has an opening 12 on the upper surface thereof and this opening is located in front of the passage 9 and is spaced from the passage 10 the same distance as passage 9 is spaced from the passage 9a. Extending in downward and forward direction from the opening 12 is the sloping passage 12a, which has its upper end at the opening 12 and its lower end at the opening 12b in the front face of the base 2, which registers with the opening 4e of the sloping passage 4c of the cylinder block 4.

The base 2 has another opening 10a on the upper surface thereof and located equidistantly from the axis of the passage 7 with the passage 12. Extending in downward and rearward direction from the opening 10a is the sloping passage 10b which has its upper end at the opening 10a and its lower end at the opening 10c in the rear face of the base 2, and which registers with the opening 3e of the sloping passage 3c of the cylinder block 3.

At the left hand end of the upper surface of the base 2, a vertical passage 13 is bored at right angles to the bore 7 in such manner as to communicate with said bore 7, as shown in Figure 4 at equal distances laterally of the opening of said passage 13 in the surface of the base 2 and equally spaced inwardly from said opening are the openings 14 and 15. Extending in downward and rearward direction from the opening 14 is the straight sloping passage 14a which has its upper end at the opening 14 and its lower end at the opening 14b in the rear face of the base 2, which registers with the opening 3f of the sloping passage 3d of the cylinder block 3. Extending in downward and forward direction from the opening 15 is the straight sloping passage 15a, which has its upper end at the opening 15 and its lower end at the opening 15b in the front face of the base 2, which registers with the opening 4f of the sloping passage 4d of the cylinder block 4.

The cylinders 3a and 4a are axially in line and are provided with pistons, 16 and 16a respectively, which are joined together by a rod 16b at a distance apart equal to that of the remote ends of said cylinders. The cylinders 3b and 4b are similarly relatively located and have pistons 18a and 18b respectively, which are similarly united by a rod 18.

For operatively and alternately connecting the openings 10a and 12 with the atmosphere and with the suction passage 9 whereby to cause reciprocation of the pistons 16 and 16a, and for alternately connecting the passage 10 with the suction passage 9a and with the atmosphere, whereby to cause pulsations of the teat-cup inflations (not shown), I provide a reciprocating valve 19, the lower face of which is shown in Figure 7. This valve is adapted to reciprocate laterally upon the right hand portion of the upper surface of the base 2, being actuated by the rod 18 which extends thereover and which is provided with downwardly projecting lugs 16a (Fig. 2) which engage against the ends of the valve 19. The valve 19 is provided with grooves 20 and 20a in the lower surface thereof, the groove 20 being adapted to connect the suction passage 9 with either of the openings 10a or 12 in the upper surface of the base 2 as the valve shifts from one extreme position to the other

extreme position, and the groove 20a being adapted to connect the passage 10 with the suction passage 9a when the valve is in the position shown in Figure 1 and to uncover said passage 10 to open it to the atmosphere when the valve shifts to its other position.

For operatively and alternately connecting the openings 14 and 15 with the suction passage 13 and with the atmosphere, I provide a valve 21, the lower face of which is shown in Figure 6. This valve is also adapted to reciprocate laterally upon the left hand portion of the upper surface of the base 2, being actuated by the rod 16b which extends thereover and which is provided with downwardly projecting lugs 16c (Fig. 3) which engage against the ends of the valve 21. The valve 21 is provided with divergent grooves 22 and 22a in the lower surface thereof, so located that one of said grooves shall cover the opening 15 and the opening of the passage 13 on the surface of the base 2, at one end of the movement of said valve, as shown in Figure 1, and the other of said grooves shall cover the opening 14 and the opening of the said passage 13 at the other end of the movement of said valve. The valve is also provided with an aperture 23 located equidistantly between the outer divergent portions of the grooves so as to register with the opening 14 at one end of the movement of said valve and with the opening 15 at the other end of the movement of said valve.

The operation of the above described device is as follows:

Assume in the first place, that the parts are in the positions indicated in Figure 1.

The tube 8 is connected to produce a vacuum in the bore 7 and cavity 5, and the tubes 11a of the manifold 11 are connected with the teat-cup inflations of the milking apparatus in the usual manner. The manifold 11 is connected to the bore 7 through the pipe 10c, the passage 10, groove 20a, and passage 9a.

The outer end of the cylinder 4a is connected through the passages 4c, 12a, groove 20, passage 9 to the bore 7, thus producing a vacuum in said cylinder. At the same time, the opening 10a being uncovered, atmospheric pressure is admitted to the outer end of the cylinder 3a, through the passages 10b and 3c, which drives the pistons 16 and 16a to the forward position, as shown in said figure, carrying the valve 19 with them by means of the lugs 16a, and bringing the groove 22 over the opening of passage 13 and the opening 14, thus connecting the outer end of the cylinder 3b with the vacuum in the bore 7, through the passages 3d, 14a, opening 14, groove 22 and passage 13. At the same time, the aperture 23 in the valve 21 registers with the opening 15, admitting atmospheric pressure to the outer end of the cylinder 4b, through the passages 15a and 4d, driving the pistons 18a and 18b to the other end of their stroke. This action carries the valve 19 with them by means of a lug 18a, thus uncovering passage 10 and the opening 12, and admitting atmospheric pressure to the teat-cup inflations through the opening 10, pipe 10c, manifold 11 and pipes 11a, and also admitting atmospheric pressure to the outer end of the cylinder 4a, through the passages 12a and 4c, and at the same time connecting the passage 3 with the opening 10a through the groove 20 and putting the outer end of the cylinder 3a into connection with the vacuum passage 7, through the passages 3c, 10b, groove 20 and passage 9.

The above cycle is automatically repeated causing the operation of the milking machine.

It will be observed that all the passages are straight and short, and that an alternative positioning of the parts will do no harm, as they are symmetrical.

While I have defined as well as I could my invention in the following claims, it is obvious that alterations including my invention could be made and I wish my claims to cover such alterations. For instance, the passages in the base may be crossed instead of the passages in the cylinder blocks.

I claim:

1. A pulsator for milking apparatus comprising, a base having a horizontal upper surface and two oppositely disposed side surfaces, two cylinder blocks each having two cylinders spaced from each other and bored therein from one vertical side surface, means securing said cylinder blocks to said oppositely disposed side surfaces with the bored surfaces adjacent thereto and the cylinders in oppositely disposed pairs, a piston in each cylinder, rods joining together in spaced pairs the pistons in the oppositely disposed pairs of cylinders, said rods passing over the horizontal upper surface of the base, a straight passage passing inclined through each block and opening at one end to one of said cylinders and at the other end through said bored side surface, a second straight passage passing inclined through each block and opening at one end to each other cylinder in the block and at the other end through said bored side surface, a pair of straight passages in said base opening through the upper surface adjacent one of the piston rods and extending inclined through the base and opening at the other ends through the side surfaces at positions to register with said passages in the blocks leading from the remote pair of cylinders, a second pair of straight passages in said base opening through the upper surface adjacent the other one of the piston rods and extending inclined through the base and opening through the side surfaces at positions to register with the passages in the blocks which lead from the other pair of cylinders, a vacuum passage in said base, apertures extending upwardly from said passage through the upper surface of said base adjacent the two piston rods, a valve operatively connected with each piston rod and adapted to slide upon the upper surface of said base, each valve having suitable open portions and being suitably positioned to connect the vacuum passage and atmosphere alternately to selected ones of the pairs of cylinders so that each pair of pistons controls the connection of vacuum to the other pair of pistons and the pistons reciprocate as long as the vacuum passage is connected to a suitable source, a teat cup connection in said base opening through the upper surface adjacent one of the piston rods, and connection means controlled by the adjacent valve for connecting vacuum to said teat cup connection each time the valve is moved to one extreme position by the piston rod.

2. A pulsator for milking apparatus comprising, a base having a horizontal upper surface and two oppositely disposed vertical side surfaces, two cylinder blocks each having two cylinders spaced from each other and bored therein from one ver-

tical side surface, means securing said cylinder blocks to said oppositely disposed side surfaces with the bored surfaces adjacent thereto and the cylinders in oppositely disposed pairs, a piston in each cylinder, piston rods joining together in spaced pairs the pistons in the oppositely disposed pairs of cylinders, said rods passing over the horizontal upper surface of the base, a straight passage passing inclined through each block and opening at one end to one of said cylinders and at the other end through said bored side surface, a second straight passage passing inclined through each block and opening at one end to each other cylinder in the block and at the other end through said bored side surface, said passages crossing each other, a pair of straight passages in said base opening through the upper surface adjacent one of the piston rods and extending inclined through the base and opening at the other ends through the side surfaces at positions to register with the passages in the blocks leading from the remote pair of cylinders, a second pair of straight passages in said base opening through the upper surface adjacent the other one of the piston rods and extending inclined through the base and opening through the side surfaces at positions to register with the passages in the blocks which lead from the other pair of cylinders, a vacuum passage centrally disposed in said base, apertures extending upwardly from said passage through the upper surface of said base adjacent the two piston rods, a valve operatively connected with each piston rod and adapted to slide upon the upper surface of said base, each valve having suitable open portions and being suitably positioned to connect the vacuum passage and atmosphere alternately to selected ones of the pairs of cylinders so that each pair of pistons controls the connection of vacuum to the other pair of pistons and the pistons reciprocate as long as the vacuum passage is connected to a suitable source, a teat cup connection in said base opening through the upper surface adjacent one of the piston rods, and connection means controlled by the adjacent valve for connecting vacuum to said teat cup connection each time the valve is moved to one extreme position by the piston rod.

3. In a pulsator for milking apparatus of the type having a central block with associated cylinder blocks upon opposite sides thereof having their faces in abutted relation, a pair of cylinder bores in each cylinder block aligned with corresponding bores of the other, interconnecting pistons in said aligned bores, and valve plates actuated by the pistons: ports defined in one face of said central block and regulated by said valve plates, ports defined in the walls of the bores in said cylinder blocks, and straight passages extending from said ports defined in said central and cylinder blocks and terminating in aligned ports in the abutting faces of said central and cylinder blocks, a different pair of said straight passages defined in said central block communicating with a pair of said straight passages in each of said cylinder blocks, said intercommunicating passages of both of said central and said cylinder blocks extending through said abutting faces at acute angles.

ROBERT W. LEMM.
